UNITED STATES PATENT OFFICE

WALTER W. LINDER, OF COOLEEMEE, NORTH CAROLINA, ASSIGNOR, BY MESNE ASSIGNMENTS, TO TERRELL MACHINE COMPANY, A CORPORATION OF NORTH CAROLINA.

MACHINE FOR CLEANING BOBBINS.

1,273,075.

Specification of Letters Patent. Patented July 16, 1918.

Application filed February 17, 1917. Serial No. 149,293.

To all whom it may concern:

Be it known that I, WALTER W. LINDER, a citizen of the United States of America, and a resident of Cooleemee, county of Davie, State of North Carolina, have invented certain new and useful Improvements in Machines for Cleaning Bobbins, of which the following is a full and clear specification.

This invention has relation to that type of 10 bobbin cleaners in which the bobbin spindle containing the waste is drawn endwise between a pair of strippers to thus scrape the waste yarn off the small end of the spindle, and the object of the invention is to improve 15 and simplify this type of machine and to increase the output to maximum, as more fully hereinafter set forth.

In the drawings—

Figure 1 is a side elevation and 20 Fig. 2 is a plan view of a machine embodying my invention;

Fig. 3 is a view, partly in end elevation and partly in vertical section, of the machine;

Fig. 4 an enlarged plan view of the main 25 parts of the machine;

Fig. 5 a view, partly in plan and partly in section, of a modified gripper device; and

Figs. 5' to 14 are views of details herein- 30 after described.

In this machine, duplicate stripping mechanisms are arranged at opposite ends of the bed of the machine, these mechanisms being brought into action alternately and 35 both sets of mechanisms being actuated from a central vertical shaft 10 arranged under the bed of the machine. This shaft is driven in any suitable manner, preferably from a transverse power shaft 11 carrying a bevel 40 gear 12 on its inner end which meshes with a crown bevel wheel 13 affixed to said shaft 10. The bevel pinion 12 is loose on the shaft 11 and is adapted to be clutched thereto by a suitable clutch 14 which is adapted to be 45 thrown into and out of operation by suitable devices that are operable from either end of the machine. In the drawing, I have shown a vertical lever 15 at each end of the machine connected together by a rod 16 which 50 is connected about midway its length by a bell crank 17 with the sliding member of the clutch, whereby an operator at either end of the machine may either stop or start the machine.

55 On the upper end of the shaft 10 is a hori-

zontal crank arm 18 which is provided at its end with a roller 19 which works in a longitudinal groove formed in a transverse bar 20, this bar being rigidly affixed to a slide plate 21 mounted to slide longitudinally in 60 the bed of the machine.

At each end of the sliding plate 21 is mounted on pivots 22 a pair of jaws 23 whose outer ends are shaped to properly grasp the wired head of the bobbin and 65 whose inner ends are normally pressed apart by means of an interposed coil spring 24, suitable vertical stop pins or lugs 25 being mounted on the sliding plate to limit the inward as well as the outward movements of 70 these jaw levers. A latch 26 is pivoted on one of the levers and extended across the other lever and adapted to engage over a lug 27 carried by said other lever to hold the gripping ends of the jaws apart, a retractile 75 spring 27' being employed to hold this latch in normal engagement with its catch lug 27.

The bobbin to be stripped is delivered by hand or by suitable mechanism, such as that hereinafter described, with its head resting 80 upon a pair of inwardly-extending plates 28 affixed to the bed plate at a point adjacent to the limit of the throw of the main slide 21, and when the adjacent end of this main slide is at the limit of its outward movement, the 85 gripping ends of the jaw levers 23 lie directly over said supporting plates 28. To assist in properly positioning the bobbin on these supporting plates 28, I provide an adjustable stop 29 which is affixed to the slide 90 plate and is adapted, when the slide plate is at the outer limit of its movement, to lie between the gripping ends of the jaws and just inside of the supporting plates 28. When the mechanism has moved the adjacent end of 95 the slide outwardly far enough to bring the gripping ends of its jaws into position to grip the bobbin head which rests upon the plates 28, an adjustable stop 30 on the bed plate of the machine automatically unlatches 100 the latch 26 and thus allows spring 24 to close the jaws upon the bobbin head, the opposite reciprocation of the sliding plate then causes the jaws to pull the bobbin inwardly along with the jaws and the plate. During 105 this inward movement of the bobbin, the waste yarn is stripped off the staff of the bobbin by means of a pair of stripping knives 31, arranged at opposite sides of the center of the machine and adapted to be au- 110

tomatically pushed inwardly to a position where they embrace the bobbin staff just behind the head of the bobbin and to be held in this position during the stripping action.

5 These knives 31 are pivotally attached at their outer ends to upright arms 32 whose lower ends are pivoted on rock shafts 33 journaled in bearings at opposite sides of the machine frame and arranged to be 10 rocked by means of cams 34 co-acting with depending arms 35 affixed to said rock shafts. The cams 34 are affixed to short shafts 36 which are driven by gears 37 affixed to said shafts 36 and arranged to mesh 15 with a driving gear 38 affixed to a short shaft 39 which is operated by a pair of bevel pinions 40 geared up to the central power shaft 10. With this mechanism, the stripping knives will be withdrawn at the end of 20 the stripping operation and will then be returned to operative position after a fresh bobbin is placed in the machine.

After the waste is stripped off the end of the bobbin staff, the waste drops into a 25 suitable hopper 41, while the bobbin is drawn inwardly toward the center of the machine and dropped into a separate hopper 42, the release of a clean bobbin from the jaws being accomplished by any suitable 30 means for compressing the inner ends of the jaw levers 23 sufficiently to loosen the bobbin from the jaws. To accomplish this release and also to reengage the latch 26 with its latch lug 27, I arrange a pair of roller stops 43 midway the length of the 35 machine in such position as to serve for both pairs of jaw levers alternately. These stop rollers 43 are arranged on the under side of a transverse plate 44^a fixed to the bed of the machine, the stop rollers being arranged 40 in the path of the jaw levers, the inner ends of the jaw levers being beveled off at 44 to form cams which strike against the rollers 43 and thus force the inner ends of the jaw 45 levers toward each other as the jaw levers pass under the plate 44^a.

When the bobbin is dropped onto the plates 28, it will be noted that the slide 21 with its stop 29 is at the inward end of its 50 stroke. It is therefore desirable to provide means for preventing the bobbin, when it thus drops on plates 28, sliding inwardly off said plates 28. For this purpose, I provide a rocking arm 45 affixed to a rock shaft 55 46 journaled on the bed frame and adapted to be rocked by an arm 47, this arm 47 being normally drawn downwardly by a spring 48 and being raised against the action of said spring by a bar-cam 49, affixed 60 to the slide plate 21 and adapted to reciprocate therewith, said arm 47 carrying a roller 50 which normally rests upon the upper inclined face of said bar-cam. The cam face of the member 49 is so shaped as to cause 65 the arm 45 to descend at the proper time to

a point just inside the supporting plates 28 to thus form a stop or bumper which will prevent the bobbin from sliding inwardly off said plates 28 when it is dropped thereon, whereby the position of the bobbin on the supporting plates 28 will be maintained until the head of the bobbin is grasped by the jaws 23. As the slide 21 brings the jaws 23 into position for grasping the head of the bobbin, the arm 45 will be raised upwardly out of the way, and the longitudinally adjustable stop 29 carried by the slide will push the bobbin into position so that the fluted parts of the jaws 23 will fit the wired head of the bobbin accurately and thus insure a firm grasp of the bobbin head. The stop 29 is made adjustable by having its screw-threaded stem tapped into the end of the slide 21, the adjusted position being maintained by a jam nut 29'. The under 80 side of the plate or arm 45 is notched at 45' to prevent this member 45 from contacting with the bobbin that is being stripped while the member 45 is descending into position to operate in connection with the succeeding 85 bobbin. One of the plates or castings 28 is grooved longitudinally at 45° to permit the arm 45 to descend into position and to also 90 guide and steady the arm 45.

In Fig. 5 I illustrate a modification of 95 the means for operating the jaw levers. In this form of the device, I pivot a cam 52 on the slide 21, at a point between the tail ends of the levers and fasten an arm 53 thereto which extends laterally and overlies the stationary part of the bed frame. A spring 54 normally pulls the tail ends of the levers together, thus tending to open the jaws. Suitable trip pins or lugs 55 are affixed to the bed plate in the path of the 100 outer end of arm 53, the position of these lugs being such that when the slide reaches the outer end of its movement the pin will 105 rotate the cam through the medium of the arm 53 and thus spread the inner ends of the levers and cause a positive gripping of the bobbin head, while at the other end of the stroke of the slide the other pin will 110 rotate the cam in the opposite direction and thus permit the spring to actuate the 115 levers to open the jaws and release the bobbin.

To feed the bobbins to each end of the machine, I employ a runway consisting of a pair of separated plates 56 arranged above 120 the bed of the machine and inclining downwardly toward the same, the lower ends of these plates being curved downwardly so as to terminate immediately above the supporting plates 28. As shown in dotted lines, the bobbins are placed in this runway with their pointed ends downwardly, the space between the plates 56 being too narrow to 125 permit the heads to pass through, so that the heads support the bobbins as they slide 130

down the runway. As the bobbins approach the curved part of the tracks, their depending ends drag upon an inclined plate 57 and thus gradually tilt the bobbins inwardly to a horizontal position, the bobbins reaching this horizontal position by the time they reach the end of the runway, so that they are in position to drop with their heads upon the supporting plates 28. The bobbins gravitate down this runway, and as fast as one bobbin is pulled away by the gripping jaws, another one automatically gravitates into position. As the small end of each bobbin drops off the forward end of drag plate 57, it falls upon a horizontal ledge or plate 58, where it rests until it is pulled into the machine by the gripping jaws. A hood 59 assists in holding the quills on the runway.

By observing Fig. 13, it will be seen that the arm 32 is connected so as to move with the rock shaft 33 through the medium of a spring connection which permits the stripping knife 31 to yield slightly when it is pressed inwardly against the bobbin staff. This yielding connection consists of an arm 60 affixed to shaft 33 and provided at its upper end with a hole through which a rod 61 freely passes, said rod 61 also passing through a lug 62 on arm 32, said bolt being provided with a head 63 engaging the outer face of the lug 62, a coil spring 64 being arranged around the bolt and kept normally pressed against the inner face of the arm 60 by means of a washer 65 on the inner end of the bolt, said washer being held in adjustable position by a suitable nut 66. With this construction, it will be observed that when the shaft 33 is rocked in a direction to force the stripping knife against the bobbin staff, the spring 64 will yield slightly and thus cause a yielding action on the bobbin staff. To normally hold the cam arm 35 against its cam and keep the stripping knife 31 normally drawn out of the path of the bobbin, I provide a coil spring 67.

In Figs. 13' and 14 I show a bobbin grasping mechanism somewhat similar to both the arrangement shown in Fig. 5 and the arrangement shown in Fig. 4. In this form of the apparatus I employ a latch 26 and its co-operating lug 27, the latch 26 being drawn normally toward the latch lug by means of a retractile spring 27'. I also employ the spring 54 which tends to normally open the jaws, and further I employ the cam 52 for spreading the inner ends of the jaws, to thus close the gripping ends thereof upon the bobbin head. The construction I have shown in these views is desirable over the construction shown in Fig. 4 in that it provides for a positive grasping of the bobbin head, and this construction shown in Figs. 13 and 14 is advantageous over that shown

in Fig. 5 for the reason that it provides for a quicker closing of the jaws. To obtain this quicker closing action, I connect the lever 53 by means of a rod 68 to a coil spring 69 inclosed in a cylinder 70 affixed to the slide 21, the arrangement being such that this spring normally tends to pull the rod 68 inwardly and thus tends to normally close the jaws upon the bobbin. The jaws are held open by the latch 26, and as soon as this latch is thrown off its lug 27 by contact with adjustable stop 30, the spring 69 (which has been by a previous action put under compression) is made free to act in opposition to the weaker spring 54, thus rotating cam 52 and quickly closing the gripping ends of the jaws upon the bobbin head. The bobbin is released at the proper point, as the slide 21 moves back toward the middle of the machine, by a stop 71 mounted on the bed frame, thus recompressing spring 69 and re-engaging latch 26, this latch 26 being pulled into position normally by spring 27'.

It will be observed that rod 68 carries a washer 72 at its rear end which bears against the rear end of the spring 69, this washer fitting cylinder 70 loosely. This cylinder is closed at its rear end and, in order to convert this rear end of the cylinder into a dash pot and thus cushion the return of the spring 69 and its actuated parts, I provide the cylinder with an air hole 73 near the rear end thereof.

The nature and scope of the invention having been thus indicated and its preferred embodiment having been specifically described, what is claimed as new is:

1. Means for feeding bobbins to a stripping machine consisting of a downwardly-inclined runway comprising a pair of separated rails between which the bobbins are suspended by their heads, said runway leading to the bobbin-head gripping devices and a drag plate arranged underneath the runway to engage the depending ends of the bobbins and tilt the bobbins as they approach the delivery point to thus deliver them in a substantially horizontal position to the machine.

2. In a bobbin stripping machine, the combination of a slide and means for reciprocating the same, a pair of pivoted gripping jaws mounted on each end of the slide, means for opening and closing these jaws as the slide reciprocates, a pair of stripping members arranged at opposite sides of the machine, a rock shaft journaled on the machine frame and connected to one of these strippers, a cam shaft provided with a cam, and an arm on said rock shaft co-acting with said cam for actuating the stripper member.

3. In a bobbin stripping machine, a bed frame, a slide mounted therein, a pair of bobbin gripping jaws at each end of the slide, a pair of stripping members on the bed frame of the machine at each end of the slide

- and means for actuating these stripper members, a bobbin-engaging abutment arm at each end of the slide, and means for automatically operating this arm.
- 5 4. In a bobbin stripping machine, a bed frame, a slide mounted therein, a pair of bobbin gripping jaws at each end of the slide, a pair of stripping members on the bed frame of the machine at each end of the 10 slide and means for actuating these stripper members, a bobbin-engaging abutment arm at each end of the slide, and means for automatically operating this arm from the movement of the slide.
- 15 5. In a bobbin stripping machine, a bed frame, a slide mounted therein, a pair of bobbin gripping jaws at each end of the slide, a pair of stripping members on the bed frame of the machine at each end of the slide 20 and means for actuating these stripper members, a bobbin-engaging abutment arm at each end of the slide, and means for automatically operating this arm from the movement of the slide, said means consisting of 25 a cam bar carried by the slide, a rock shaft journaled on the frame and a rocker arm attached to the rock shaft and normally engaging said cam bar.
6. In a machine of the class set forth, a 30 bobbin rest, a slide carrying a pair of bobbin grasping jaws, means for operating said jaws and said slide, and an adjustable bobbin adjuster adapted to position the bobbin head properly with respect to the jaws, said adjuster being carried by the slide.
7. In a machine of the class set forth, a 35 pair of reciprocating bobbin grasping jaws and means for operating the same, a pair of stripping knives arranged at opposite sides 40 and means for operating these knives, this latter means consisting of a cam operated rock shaft, an arm pivotally mounted on said rock shaft and connected to one of the
- knives, and a resilient connection between this arm and the rock shaft whereby the engagement of the knives with the shaft of the bobbin will be a resilient one.
8. In a machine of the class set forth, a slide and means for reciprocating the same, a pair of jaws pivotally mounted upon the 50 slide and means normally tending to open the jaws, means tending to normally latch the jaws open, and positively operated means for tripping said latch and overcoming the normal tendency of the jaws to be 55 held open.
9. In a machine of the class set forth, a slide and means for reciprocating the same, a pair of bobbin gripping jaws pivotally mounted on said slide, a spring tending to 60 hold these jaws normally open, a latch device normally tending to latch the jaws open, a latch-releasing device arranged to operate when the jaws are in position to grasp the bobbin, and an automatically-operated quick-opening means for the jaws including a spring more powerful than the aforesaid spring and a tripping device for putting said powerful spring into action when the latch is released.
10. In a machine of the class set forth, a 65 bobbin rest, a slide carrying a pair of bobbin grasping jaws, means for operating said slide and said jaws, a bobbin adjuster located on the slide at a point just behind and between the jaws and adapted to positively engage the bobbin head and push it into proper position for grasping by the jaws, means being provided for adjusting said adjuster toward and from the bobbin rest.
- In testimony whereof I hereunto affix my signature.
- WALTER W. LINDER.
- Witness:
JAMES W. ZACHARY.
